ELECTRICAL TRANSFORMER

Frank A. Koditek, Lynn, Mass., and Roger B. Kerr, Jamestown, R. I., assignors to General Electric Company, a corporation of New York

Application October 28, 1954, Serial No. 32,860

Term of patent 14 years

(Cl. D26—15)

Fig. 1

Fig. 2

Fig. 3

Fig. 1 is a front perspective view of an electrical transformer embodying our new design;

Fig. 2 is a top view of the transformer shown in Fig. 1, and

Fig. 3 is a side elevational view thereof.

The dominant features of our design reside in the portions shown in full lines.

We claim:

The ornamental design for electrical transformer, as shown and described.
